(57) **CLAIM**

The ornamental design for a multi-functional straight folding LED work light, as shown and described.

DESCRIPTION

FIG. 1 is a perspective view of the multi-functional straight folding LED work light showing my new design;

FIG. 2 is a bottom plan view thereof;

FIG. 3 is a rear elevation view thereof

FIG. 4 is a top plan view thereof;

FIG. 5 is a left side elevation view thereof;

FIG. 6 is a right side elevation view thereof; and,

FIG. 7 is a front elevation view thereof.

Throughout the drawings the broken lines depict portions of the multi-functional straight folding LED work light that form no part of the claimed design.

1 Claim, 4 Drawing Sheets
